R. S. DILLON.

Heating Stove.

No. 95,206.

Patented Sept. 28, 1869.

Attest,

*H. T. Everts
Jas. J. Day*

Inventor
R. S. Dillon
Per Attorney
Ross Sprague

United States Patent Office.

RICHARD S. DILLON, OF DETROIT, MICHIGAN.

Letters Patent No. 95,206, dated September 28, 1869.

COAL-STOVE.

The Schedule referred to in these Letters Patent and making part of the same.

To whom it may concern:

Be it known that I, RICHARD S. DILLON, of Detroit, in the county of Wayne, and State of Michigan, have invented a new and useful Improvement in Heating-Apparatus; and I do declare that the following is a true and accurate description thereof, reference being had to the accompanying drawings, and to the letters of reference marked thereon, and being a part of this specification.

The drawing is a vertical section of my invention, the nature of which relates to an improvement in the construction of stoves and furnaces for heating-purposes, wherein all the particles of carbon, smoke, and gases liberated in the combustion of coal may be entirely consumed, said device being best adapted to the economical consumption of bituminous coal.

The invention consists in the arrangement, within the shell of the stove, of a reverberatory chamber, in which the combustion commenced in the fire-chamber is completed by the admixture of air, in suitable proportions, with the gases, at proper points in said chamber, so that the entire products of combustion shall be consumed within the stove, thereby utilizing all of the heating-properties of the coal.

It also consists in a peculiar arrangement of an air-chamber and tubes, for delivering atmospheric air to the reverberatory chamber, and in the general arrangement of all the parts.

In the drawings—

A represents the cylindrical body of my improved stove, terminating in a contracted neck, A'.

The stove is fitted with a chute, B, through which the fire is replenished with fuel when necessary.

It is also provided with the usual grate, draught-door, and ash-pan.

Surrounding the neck of the stove is an air-chamber, C, provided with registers, c, through which air may be admitted to the interior of the chamber.

The air is broken into minute jets, by being compelled to pass through a perforated diaphragm, E, which is placed within the chamber.

Surmounting the walls of the air-chamber is an annular conical flange, D, whose inner periphery turns up and terminates at the level of the top of the neck of the stove, leaving an annular air-space between it and the neck.

Surmounting the flange D, and flanged on its inner periphery, is a flue, F, having an encircling deflecting-flange, f, at its top.

The material of which this flue is constructed is fire-brick, or fire-clay, or other heat-retaining and radiating material.

G are air-tubes, rising from the air-chamber, and support a gas-ring, H, in which their upper ends terminate.

I is a reverberating-chamber, closed at the top, and

resting, by its flange i, on the gas-ring H, leaving an annular space between the flange i and the exterior of the flange D.

The reverberating-chamber I is constructed of the same refracting-material as the flue F, and its arch or crown, I', may be strapped with iron to strengthen it.

Surrounding the reverberatory chamber I is a radiator, J, which may be of sheet or cast-metal, and is provided with an outlet, j, at the top, to which a proper pipe is attached to maintain the draught.

The operation of this improvement is as follows:

A suitable fire is made in the body of the stove. As soon as the walls of the flue F and chamber d become highly heated, from the passage of the flame and gases in contact with them, the registers c are opened, and a supply of oxygen is admitted to the air-chamber C, passing through the perforated diaphragm E, when it is subdivided into numerous small jets, and rising through the annular spaces between the neck and flange, comes into contact with the products of combustion, with which it mixes, and causes them to ignite.

The flames pass up to the crown of the reverberatory chamber, when the draught will bring them around the flange f of the flue, and down into the space between the flue and outer walls of the chamber.

The enlarged area of this space gives the oxygen ample room to mix with the gases and ignite them, the admixture being promoted by the currents being retarded by the flange f, which serves as a bridge-wall, breaking up the currents.

The currents then pass down between the flange i of the chamber and the base of the flue, and the flames receive a fresh but limited supply of air through the air-tubes G and gas-ring H, under the flange; and as they pass up between the outer walls of the reverberatory chamber and the radiator J, should there be any unconsumed particles of carbon in the current, or unignited gases, they are ignited and totally consumed, perfect combustion being the result, and the greatest possible amount of heat radiated from the stove and radiator-case.

The walls of the flue and reverberatory chamber being heated to a high degree, small particles of unconsumed carbon readily ignite from the heat radiated from said walls and chamber, combustion being promoted by bringing a fresh supply of oxygen into contact with them, in the manner described.

The perforated diaphragm-plate E also serves to make the supply of air even in its current to the flame.

What I claim as my invention, and desire to secure by Letters Patent, is—

1. The arrangement of the annular air-chamber C,

provided with registers *c*, the conical deflector-flange *D*, air-tubes *G*, and gas-ring *H*, with or without the perforated diaphragm *E*, substantially as herein specified, and for the purpose mentioned.

2. The flue *F*, provided at its top with the outward-projecting flange *f* and the reverberatory chamber *I*, provided with an internal flange, *i*, arranged within a radiator, *J*, substantially as and for the purpose herein set forth.

3. The arrangement of the foregoing-named parts with the body **A** of a stove or furnace, having a contracted neck, *A'*, when constructed, combined, and operating substantially as and for the purposes herein described.

RICHARD S. DILLON.
